Primary Examiner — Eric L Goodman*Assistant Examiner* — Lilyana Bekic(57) **CLAIM**

The ornamental design for a flex conduit for a breast pump system, as shown and described.

DESCRIPTION

FIG. 1 is a front perspective view of a flex conduit for a breast pump showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dash-dash broken lines in the drawings depict portions of the flex conduit for a breast pump that form no part of the claimed design.
